FIG. 5.

UNITED STATES PATENT OFFICE

WILLIAM F. PUNTE, OF SYRACUSE, NEW YORK, ASSIGNOR TO CONTINENTAL CAN COMPANY, INC., OF NEW YORK, N. Y., A CORPORATION OF NEW YORK

METAL CONTAINER

Application filed November 11, 1930. Serial No. 494,968.

The invention relates to new and useful improvements in easy opening metal containers wherein the cover is secured to the container body by a sealing ring.

5 An object of the invention is to provide a container of the above type with a sealing material so arranged that the sealing ring makes contact therewith and establishes through the aid of said sealing material a 10 seal for the container whereby when said sealing ring is removed the seal will be broken thus permitting the cover to be easily removed from the container.

15 A further object of the invention is to provide an easy opening container of the above type wherein the cover is so constructed as to make friction reclosure with the container body.

In the drawings:

20 Fig. 1 is a sectional view through a container embodying the improvements.

Fig. 2 is an enlarged sectional view through the upper portion of the container. With the ring applied and prior to the turning of 25 the flange to compress the sealing material.

Fig. 3 is a view similar to Fig. 2 but showing the flange turned to compress the material for establishing the seal.

Fig. 4 is a side view of a container after it 30 is sealed.

Fig. 5 is a plan view of a portion of a blank from which the strip is formed.

Fig. 6 is a view similar to Fig. 3 but showing a slightly modified arrangement of construction.

The invention is directed to a container consisting of a body portion having an open end and the metal at the open end of the body portion is bent preferably inwardly so as to 40 form a bead and conceal the raw edge of the metal. The body is provided with a bend in the wall thereof forming a shoulder on the outer face of the container which is disposed adjacent the bead at the end of the body wall.

45 The cover is preferably provided with a depression which snugly fits within the bead at the end of the container body. The cover has an outwardly extending flange which is bent downwardly to form a skirt which slips down 50 over the outside of the bead, said skirt is pref-

erably inturned so as to protect the raw edge of the metal. A sealing material is placed against the shoulder in the body wall and against the lower end of the skirt which is on a line therewith and a sealing strip is applied 55 for securing the cover to the container and sealing the same, said strip has a portion overlying the cover, a portion extending vertically along the outside wall of the skirt to a point below the same and said lower portion 60 of the sealing ring is turned underneath and pressed against the sealing material for sealing the container.

Referring more in detail to the drawings, the improved container consists of a body portion 1, preferably made of sheet metal and cylindrical in form. To one end of the body portion is attached a closure 2 which is secured thereto by a double seam 3. The other end of the body wall is rolled or curled inwardly as indicated at 4. This forms a bead at the end of the body wall and conceals the raw edge of the metal. This makes a smooth edge at the end of the body wall which is the 70 open end of the body when the container is opened. It also strengthens the open end of the body so as to maintain it in its rounded form.

The wall of the body portion 1 of the container is inset or contracted as indicated at 5 80 and this forms a shoulder 6 in the body wall on the outer face thereof which is disposed a short distance from the bead 4 at the extreme outer end of the body wall.

85 The container is closed by a cover 7. This cover has a depression formed therein providing a vertical friction wall 8 which extends down inside of and makes contact with the inner edge of the bead. The cover has a portion 9 which overlies the bead and a depending skirt 10. This depending skirt 10 is 90 folded back upon itself as indicated at 11. The folded skirt extends down outside the body wall and along the outer face of the bead at the upper end of the body wall. The skirt 95 is of such length that the lower edge 12 thereof is substantially on a line of the outer face of the shoulder 6 in the body wall. A sealing ring 13 is placed against the shoulder 6 and the lower edge 12 of the skirt 10. 100

The cover is attached to the container body by means of a sealing strip 14, said sealing strip 14 is provided with a projecting finger or tab 15 at one end thereof which is adapted to overlie the other end 16 of the strip when it is shaped into ring form. The sealing strip is bent so as to provide a horizontal portion 17 which extends all the way across the portion 9 of the cover 7. The inner edge 18 of the strip extends slightly downward into the depression in the cover and below the plane of the extreme outer edge of the part 9 of the cover. This strip 14 has a vertical portion 18 which extends downwardly along the outer wall of the skirt 10 and to a distance below the sealing ring 13 when it is first applied to the container. The parts described are shown in Fig. 2. The ring is held firmly seated against the cover and the lower part of the vertical portion 18 of the ring is turned beneath the sealing material as indicated at 19 in Fig. 3 of the drawings. As it is turned beneath this sealing material it is pressed upwardly against the same and forces the sealing material into contact with the lower edge portion of the skirt and the shoulder portion 6 and in between the skirt and body wall to a sufficient extent to hermetically seal the container. The spinning of the lower edge of the sealing strip beneath the sealing material and the extending of the horizontal portion thereof all the way across and a slight distance down into the depression serves to firmly hold the sealing strip in place although the ends thereof are not locked together. It will be understood that from certain aspects of the invention other forms of sealing strips or rings may be used but in the form shown and described the ends are not joined but one end is provided with a tongue or tab which overlies the other so that it may be readily grasped and the sealing strip forcibly pulled and removed from the container. When the sealing strip is so removed it will release its pressure on the sealing material and allow the sealing material to be readily removed and thus break the seal of the container. This has an advantage where containers are put under vacuum as the breaking of the seal by the removing of the sealing strip breaks the vacuum holding the cover on the container and permits the cover to be readily slipped off from the container. There is a sufficient frictional grip between the metal parts of the cover and the metal parts of the container body so as to hold the cover in place for reclosure purposes. This frictional grip may be obtained between the outer skirt and the outer wall of the container or between the vertical wall of the depression and the inside of the bead on the body of the container or through both if desired.

In Fig. 6 of the drawings a slightly modified form of construction is shown. In this

form the wall of the container body is outset or bent outwardly directly below the bead formed at the outer end thereof and the depression in the cover snugly fits the inner face of the bead reaching below and contacting with the inner face of the body wall below the bead. In this form of construction the inner edge of the sealing ring is also shown as fluted as indicated at 20. It is the points formed by the fluting of the edge extending over into the depression in the cover that retain the sealing ring in place on the container. This facilitates the removing of the sealing ring as a pull on the sealing ring will bend the points so as to release their gripping contact with the cover. 70 75 80

It is understood, of course, that this connection of the cover to the container body is made by the manufacturer of the container and is not really the bottom of the container until it is packed with the food product, after which the closure 2 is applied and double seamed to the container. This application of the closure to the container body after it is packed is, of course, made by the packer. 85 90

When it is desired to open a container the sealing ring may be readily removed by grasping the tab or finger 15 and with a pull thereon the sealing ring will be stripped from its engagement with the container. 95 The container after it is thus opened may be readily reclosed by slipping the cover back onto the container body where it will be held in place by the frictional grip of the metal parts although the container will not be re-sealed. 100

It is obvious that minor changes in the details of construction and arrangement of parts may be made without departing from the spirit of the invention as set forth in the appended claims. 105

Having thus fully described the invention what is claimed as new and is desired to be secured by Letters Patent is:

1. A metal container including in combination a body portion having an offset therein adjacent one end thereof forming a shoulder on the outer face of the body, a cover for said container having a depending skirt adapted to extend along the outer face of the body wall of the container and terminating substantially at said shoulder, said cover having a depression therein extending into the container, a sealing material engaging said shoulder and the lower edge of the skirt, a sealing member having a portion overlying the cover and extending into the depression in the cover and having a vertical portion extending along said skirt below the sealing material and adapted to be turned inwardly against the sealing material for firmly clamping the same against the shoulder on the container body and the edge of the skirt for sealing the container. 110 115 120 125

2. A metal container including in com-

bination a body portion having the end of the body wall rolled inwardly to form a bead, said body wall below the bead being offset to form a shoulder on the outer face of the

5 body, a cover for said container having a depending skirt adapted to extend along the outer face of the body wall of the container and terminating substantially in said shoulder, said cover having a depression therein

10 extending into the container, a sealing ring engaging said shoulder and the lower edge of the skirt, a sealing strip having a portion overlying the cover and extending into the depression in the cover and having a vertical portion extending along said skirt below the sealing material and adapted to be turned inwardly against the sealing material for firmly clamping the same against the shoulder of the container body and against the

15 edge of the skirt for sealing the container.

3. A metal container including in combination a body portion having the end of the body wall rolled inwardly to form a bead and having an offset in the body wall adjacent the bead and forming a shoulder on the outer face of the body, a cover for said container having a depending skirt adapted to extend along the outer face of the body wall of the container and make frictional

30 contact therewith, said skirt being bent inwardly and upwardly and having the lower edge thereof terminating substantially at the shoulder, said cover having a depression therein extending into the container, a sealing ring engaging said shoulder and the lower edge of said skirt, a sealing strip having at one end thereof a projecting tab adapted to overlie the other end of said strip when attached to the container, said sealing strip

35 having a portion thereof overlying the cover and extending into the depression in the cover and having a vertical portion extending along said skirt below the sealing material and adapted to be turned inwardly against the sealing material for firmly clamping the same against the shoulder on the container body and the edge of the skirt for sealing the container, whereby when the strip is

40 removed the sealing material is released and the seal of the container broken and whereby when said sealing strip is removed said cover may be applied to the container body and serve as a frictional reclosure therefor.

4. A metal container including in combination a body portion, a cover for said container having a depending skirt adapted to extend along the outer face of the body wall of the container, a sealing gasket arranged outside of said container body for sealing the opening between the container body and the cover flange, a metal sealing ring having a portion overlying the cover and a portion encircling and covering said sealing gasket and firmly pressing said gasket

50 into contact with the container wall and
